DESIGN FOR A SPECTACLE FRONT

Emanuel Pappert, Flushing, N. Y., assignor to The
Ful-Vue Sales Company, Washington, D. C.

Application June 17, 1933, Serial No. 48,435

Term of patent 14 years

To all whom it may concern:

Be it known that I, EMANUEL PAPPERT, a citizen of the United States, residing at Flushing, in the county of Queens and State of New York, have invented a new, original, and ornamental Design for a Spectacle Front, of which the following is a specification, reference being had to the accompanying drawing, forming a part hereof.

Figure 1 is a perspective view on an enlarged scale of one of the lens straps shown in Fig. 2.

Figure 2 is a front elevation of the spectacle front showing my new design.

The dominant feature of my design resides in the particular ornamental configuration of the lens straps.

I claim:

The ornamental design for a spectacle front substantially as shown and described.

EMANUEL PAPPERT.
